UNITED STATES PATENT OFFICE.

INEZ E. RISLEY, OF LOS ANGELES, CALIFORNIA.

FIT-EASY FACING FOR HATS.

Application filed February 23, 1926. Serial No. 90,018.

My present invention relates to what I may term fit-easy facings—designed for use in the lining and ornamentation of hat brims. My invention includes made-up fac-
5 ing units which are suitable for distribution as articles of manufacture and are in-
tended to be handled through the usual
channels of wholesale and retail millinery
trade; and, for this purpose, my brim-
10 facing units may be separately enclosed in
“glassine paper” envelopes, or the like, per-
mitting the same to be easily inspected with-
out risk of damage,—as for the purpose of
selecting a size or shape or color to give
15 a desirable ensemble effect.

It is an object of this invention to relieve milliners of a large part of the labor, anx-
iety and delay heretofore incidental to the
providing of a colored or decorative facing
20 beneath the brim of a selected hat. Hereto-
fore, in order to provide for the facing of
a brim, the customer who may have pur-
chased (and may be wearing) a given hat
has been required to visualize the effect
25 likely to be obtained by, (1) cutting a piece
of silk or other facing material from yard-
age, (2) cutting a piece of reinforcing wire
from a coil or reel thereof, (3) simulta-
neously and laboriously fitting and (4) se-
30 curing these elements beneath the outer edge
of the brim of the hat to be faced, (5) cut-
ting and (6) inserting and (7) securing the
inner edge of this selected facing material
while (8) gathering the same,—these opera-
35 tions being presumably followed by (9) the
stitching-in of a lining and by a (10) final
steaming and (11) pressing of the whole—
all of said operations requiring time, skilled
labor, taste and involving the delays and
40 mishaps unavoidably incidental to any
made-to-order business; it is an object of
this invention to simplify the above opera-
tions by enabling any “prospect” to look
over and select from a stock of preformed
45 brim-facings, each comprising the men-
tioned members but assembled independ-
ently of any hat and made up in standard
and assorted shapes, sizes, colors and de-
signs. The selected facing—perhaps chosen
50 with special regard to the matching color
in a dress purchased subsequently to a hat
which is to be brought into harmony therewith—is thus quickly applicable, in the
presence of the customer, as for the purpose
55 of immediate wear.

Other objects of my invention, including

preferred sequences of assembly and organi-
zations which comprise not only facings
proper, with their requisite reinforcements,
but also additional decorative members 60
adapted to be disposed either above or below
hat brims—according to the character of the
same and/or the taste of the wearer—will be
appreciated from the following description
of alternative embodiments of my invention, 65
taken in connection with the appended
claims and the accompanying drawings, in
which

Fig. 1 is a top plan view illustrating a
made-up brim facing or hat-finishing unit 70
as enclosed, for storage and/or transport
and/or display and/or sale in a transparent
envelope.

Fig. 2 is a diagrammatic view illustrating,
as in vertical section on the line 2—2 of Fig. 75
1, a made-up facing unit of the same general
character.

Fig. 3 is a perspective view of a hat pro-
vided with an embodiment of my invention
similar to that shown in the preceding fig- 80
ures, with parts broken away.

Fig. 4 is a diagrammatic perspective view
showing, in vertical section, a hat comprising
a crown and a brim, and showing also a
facing unit adapted to be applied thereto. 85

Referring to the details of that simple em-
bodyment of my invention shown diagram-
matically in Fig. 4, 11 may be a main textile
member cut from a web of suitably colored
silk, or from selected facing material and 90
adapted to contact with the brim of the hat
to be trimmed, this member having the form
of a flat band resembling in area and form
the brim 12 of the hat to be finished or
decorated thereby; the outer edge 13 of the 95
facing 11 may be provided with a neat hem
enclosing a reinforcing hoop 14, of wire, or
the like; and the inner edge 15 of the facing
material 11 may be carried upward within
a textile band reinforcement 16, conical in 100
general shape, formed of so-called spiretta
or a similar material,—this band reinforce-
ment being secured to the facing material
by means such as one or two rows of ma-
chine stitching 17.

Whether or not the facing 11 is initially
in the form of a completely or approxi-
mately straight strip, the inner edge thereof
being then preferably gathered or pleated in
a uniform or attractive manner during the
application of the same to the mentioned
reinforcing members (assuming that said 110

facing material is not provided by merely cutting a substantially circular or elliptical hole in a substantially circular or elliptical piece of material) it may advantageously be 5 cut on a bias,—the ends of the facing strip being secured together, as by stitching in a diagonal line, as suggested at 18; and the ends of the spiretta or other band reinforcement may be simply overlapped and sewed together in a manner favorable to reliance upon a final pressing operation in bringing the inner edge of the resultant brim-facing unit or organization into a satisfactory fitting relationship with the inner edge 19 of 15 the hat to which said unit may presently be secured.

If desired, and in order to satisfy the requirements of more exacting patrons, I may, as suggested in Fig. 2, associate with a facing material 11^a, reinforced by a peripheral hoop 14^a and by a band 16^a (both laps of the facing material being shown, in Fig. 2, as retained by one or more rows of stitching 17^a) an outer web 20^a of a preferred diaphanous or other decorative material, preferably embroidered or otherwise decorated somewhat as suggested in Figs. 1 and 3. The periphery of this additional and diaphanous layer may be reinforced, like the 20 periphery of the facing material 11 or 11^a, by means of a wire or other hoop 14^a; and, if desired, this wire or hoop may be associated with and concealed by additional reinforcing and decorative members such as a 25 tape 21^a and/or a fringe strip 22^a,—all of these peripheral reinforcing or decorative elements being optionally secured by a row or rows of stitching 23^a,—serving incidentally to provide a hem at the outer edge of 30 the diaphanous or other material 20^a.

I prefer not to utilize the machine stitching 17^a, or other permanent stitching, in securing the diaphanous material 20^a to the inner reinforcing band 16^a, of spiretta, or its 35 equivalent, relying rather upon a limited number of hand stitches, as suggested at 24^a, to so secure the mentioned diaphanous material as to facilitate the momentary removal of said diaphanous material, with its peripheral reinforcement and/or decoration, as for 40 the purpose of applying the same above a hat brim 12^a, in the general manner suggested in Fig. 3. That is to say, although a complex hat-finishing or brim-facing unit 45 or organization of the general character illustrated in Fig. 2 may, if desired, be disposed entirely beneath a hat brim (as by the use of a few stitches in securing the peripheral reinforcing member and the band reinforcing member relatively to the respective edges of a brim) it is an important merit of brim-facing or hat-finishing organizations of the general type illustrated in Figs. 1, 2 and 3, that the diaphanous member 20^a, or 50 its equivalent, this being detachably secured

by relatively few stitches 24^a to the central reinforcing band 16^a, or its equivalent, may be quickly and easily separated therefrom, as for the purpose of disposing the said diaphanous member, with its peripheral reinforcement and/or decoration above the brim of a hat, one or more rows of stitching 25^a being employed for the attachment of the same and optionally also for the purpose of providing a hem at the upper or inner edge 55 of said member,—where the same may contact with the crown 26^a of the selected hat.

It will be appreciated that, whether or not stitched and sewed together as above described, the diaphanous member 20^a, or its equivalent, with any desired peripheral reinforcement and/or ornamentation may optionally be applied to a hat distinct from that to which the facing material 11^a, or its respective reinforcements, may be attached; and, as implied above, my facings may be made up from a great variety of materials, very diverse in color and in ornamentation, two or three different widths of brim being optionally provided for in each of the shades 60 or colors popular during a particular season.

It will, however, be appreciated that my facing units need not exactly correspond in diameter with the brims of the hats to which they are applied,—it being entirely practicable to stitch the reinforcing members 14, 14^a, etc. at a uniform or varying distance from the outer edge of a hat brim, and practicable also to permit either an opaque facing or a diaphanous member, such as the member 20^a, to extend beyond the edge of or to replace a brim; and, even though my brim-facing and hat-finishing units may vary within wide limits in type and in dimensions, they may, if desired, be enclosed in uniform glassine 65 or other envelopes 27^a, to protect the same during storage, transport, display, and sale,—the ordinary purchaser being presumably qualified quickly and easily to attach the same to any hat previously or simultaneously purchased; and the cost of my described units may be so low as to encourage the frequent substitution of facings, as for the purpose of giving an old hat the appearance of newness or for the purpose of bringing a selected old or new hat into harmony 70 with selected costumes,—linings, not shown, being stitched therein.

Although I have herein described alternative embodiments and uses of my invention, it will be appreciated not only that various features of my invention might be independently employed, but also that numerous additional modifications might be devised, by those skilled in the art to which this case relates, without involving the slightest departure from the spirit and scope 75 of my invention, as the same is indicated above and in the following claim.

By "hoop-like", in said claim, I mean to 80

refer to reinforcing elements, such as wires, which tend to maintain a circular or elliptical general form; and by "spiretta-like" I mean to refer to a light and flexible textile material having a somewhat open mesh but having stiffness enough to assure a tendency toward the retention of a form (as, a conical form) imparted to the same by pressing.

I claim as my invention:

10 As an article of manufacture, a made-up brim facing unit for hats comprising: a main textile member in the form of a flat

web made endless and adapted to contact with the surface of the brim of the hat on which said facing unit is to be used; a circumferentially extending reinforcement and a web of diaphanous material provided with peripheral reinforcement, detachably secured to said textile member reinforcement.

In testimony whereof, I have hereunto set my hand at Los Angeles, California, this 15th day of Feb., 1926.

INEZ E. RISLEY.
